ELECTRIC SWITCH

George N. Lemmon, Homewood, and Harry H. Knowles, Birmingham, Ala.

Application December 30, 1931, Serial No. 583,802

8 Claims. (Cl. 200—48)

The main object of our invention is to provide a contact which shall have a slight but positive sliding action between the conducting members as they come together when closing the circuit.

5 A further object is to provide a simplified support for the flexible conductor which is part of the switch.

Referring to the drawing, Fig. 1 shows in elevation a side-break switch embodying our device; Fig. 2 is an elevation of our rocker-type switch. Both of these designs are well known to those familiar with the art. Fig. 3 shows in partial section an enlarged detail of the contacts in the opening or closing position, and Fig. 15 4 is a similar detail with the contacts closed.

In Fig. 1, a base 1 carries a stationary insulator 2 and a movable insulator 3 which is rotated by the crank 3'. Securely fastened to 3 is a conducting arm 4, and the conductor 14 is connected to 4 by a pivot and the flexible lead 13. On the insulator 2 is a housing 10 within which is a movable contact member which engages with the end of 4. Flexible conductors 11 furnish a positive connection between this movable contact member and the line conductor 12.

In Fig. 2, the base 1 carries two stationary insulators 2 and 20 and a movable insulator 3. This is attached to the rockable square shaft 25 and carries a conductor 4 with a contacting terminal 5. Insulator 2 carries the housing 7, pivoted about the pin 9 and supporting the movable contact member 6, which is biased outwardly by the springs 8. The housing 7 is biased to the angular position shown in Fig. 3 by the spring 24, and the stop 25 limits the motion of 7 to the desired travel. As the switch is closed, 7 and 4 are brought into the straight line position shown in Fig. 4. This action is quite similar to the action shown in our Patent No. 1,955,132 issued 40 April 17, 1934.

However, the contacts 5 and 6 come together before the position shown in Fig. 4 is reached, and as the two engaging faces have curves with the same radius, they engage over a considerable 45 part of the curve. Further motion of the conductor 4 towards the closed position causes a sliding action of 5 over the surface of 6, which continues until the position shown by Fig. 4 is reached. This motion pushes 6 into its housing 7, and in doing so the springs 8 are compressed. Having the curved face of 6 off center, as shown, gives a greater angularity of contact between the point 6' and 5. This prevents the point 6' from sticking to 5 where they first touch each 55 other, and makes 6 and 5 slide around on one

another as the switch is being closed the rest of the way.

This sliding action tends to rub off any dirt or corrosion, and this insures a good contact between the parts.

For switches of large capacities, two or more members 6, each with its flexible conductors 11 and its springs 8, are mounted in a single housing 7, and the contact end 5 is lengthened into a cylindrical surface which engages with all of 10 the members 6. Each of these members 6 makes its own contact with 5, independently of the other members, and the conductors 11 give proper connection with the line 12. In the side-break switch shown in Fig. 1 parts similar to 6, 7, 8 and 15 9 are mounted under the housing 10; and these parts in both switches function similarly.

If the rocker-type of switch is employed, as shown in Fig. 3, then we support the flexible conductor 13 by means of an arm 15 which is pivoted 20 at 16 and carries a ring 17 through which the conductor 13 passes freely. It is quite customary to support this long flexible lead, which is not self-supporting, by a pantograph consisting of two arms, one like 15 except for the stop 18, and 25 another which is pivoted to the cap on insulator 3 and is also pivoted to 15 at its end 17. Such a pantograph is made longer than the maximum straight distance from the pivot 18 to the corresponding pivot on top of the insulator 3. Therefore the pantograph cannot drop down, and so the conductor 13 is held up in a safe position and is not allowed to sag down towards the grounded metal base, whether the switch is open or closed. We support the flexible conductor safely, and 30 have the wide, free motion of a pantograph while using only one supporting arm.

A stop 18 rests against the head 19 of the insulator 20 and limits the downward motion of 15. When the insulator 3 is rocked backwards 40 towards 20, the switch is opened and the arm 15 takes the position 21 as the conductor 13 is pushed back and takes the position 22. In this way, the flexible conductor is held up in a safe position without the use of a complete pantograph such 45 as is generally used for this purpose.

We claim:

1. In an electric switch, a stationary conducting member, a flexible conductor connected therewith and extending away from said member, a 50 rigid arm pivotally supported at one end only, said arm supporting the said flexible conductor.

2. In an electric switch, a stationary insulated support and a movable insulated support, a flexible conductor between them, and a rigid member 55

- which is pivotally supported at one end only and which is arranged to hold up the center portion of the said flexible conductor.
3. In an electric switch, a stationary conducting member, a flexible conductor connected therewith and extending away from said member, an arm pivotally supported at one end only, by the said stationary member, said arm supporting the said flexible conductor.
4. In an electric switch, a stationary conducting member, a pivotally mounted arm thereon, a stop limiting the downward travel of the arm, and a flexible conductor supported by the free end of the arm.
5. In an electric switch, two movable members with abutting contact faces in a plane transverse to the plane of movement, the face of one member in its normal closed position extending beyond the face of the other member in its normal closed position, together with means to allow one member to be pressed back from its normal position.
6. In an electric switch, two movable members with abutting contact faces in a plane transverse to the plane of movement, the face of one member in its normal closed position extending beyond the face of the other member in its normal closed position, together with means to bring
- the said faces into contact before the members reach the fully closed position of the switch, and to slide the faces over one another as they move into the fully closed position.
7. In an electric switch, two movable members with curved abutting contact faces in a plane transverse to the plane of movement, one face being curved inwardly and the other curved outwardly, the face of one member in its normal closed position extending beyond the face of the other member in its normal closed position, together with means to allow one member to be pressed back from its normal position, and with means to bring the said faces into contact before the members reach the fully closed position, and to slide the faces over one another as they move into the fully closed position of the switch.
8. In an electric switch, a movable conducting member having an outwardly curved contact face across its end, a second movable conducting member having an inwardly curved contact face in juxtaposition to the said first contact face, together with means to bring the said faces into contact and rub them together, as the switch is being closed.
